N. F. LOCKWOOD

Des. 122,316

CLOCKCASE

Filed July 9, 1940

Inventor:
Norman F. Lockwood,
by Harry C. Dunham
His Attorney.

UNITED STATES PATENT OFFICE

122,316

DESIGN FOR A CLOCKCASE

Norman F. Lockwood, Providence, R. I., assignor to Warren Telechron Company, a corporation of Maine

Application July 9, 1940, Serial No. 93,520

Term of patent 7 years

To whom it may concern:

Be it known that I, Norman F. Lockwood, a citizen of the United States, residing at Providence, in the county of Providence, State of Rhode Island, have invented a new, original, and ornamental Design for a Clockcase, of which the following is a specification, reference being had to the accompanying drawing forming a part thereof.

The figure is a front perspective view of a clockcase showing my new design.

I claim:

The ornamental design for a clockcase, as shown.

NORMAN F. LOCKWOOD.
